United States Patent Office.

JOSEPH HARRISON, JR., OF PHILADELPHIA, PENNSYLVANIA.

Letters Patent No. 100,141, dated February 22, 1870.

IMPROVEMENT IN STEAM-GENERATORS.

The Schedule referred to in these Letters Patent and making part of the same.

I, JOSEPH HARRISON, Jr., of Philadelphia, county of Philadelphia, State of Pennsylvania, have invented an Improvement in Steam-Generators, of which the following is a specification.

Nature and Object of the Invention.

My invention relates to improvements fully described hereafter in the cast-iron steam-generator for which Letters Patent were granted to me on the 4th day of October, 1859, my present improvements having been made with a view of strengthening the necks of the groups of spheres of which the boiler is composed, and of so jointing the spheres and arranging them in sections or slabs that the latter are capable of yielding at every point where a joint occurs when subjected to unequal expansion and contraction.

Description of the Accompanying Drawing.

Figure 1 represents a vertical section of a portion of a steam-generator with my improvements;

Figure 2, a sectional plan on the line 1-2, fig. 1;

Figure 3, a transverse section on the line 3-4, fig. 1;

Figure 4 illustrates the improved mode of arranging the spheres so as to form the section or slab of a generator; and

Figure 5 is a sectional plan on the line 5-6, fig. 4.

General Description.

The steam-generator described in my patent of October 4, 1859, consisted of a number of spherical chambers cast in groups and united by curved necks, the joints between the groups being united by bolts passing through the said spherical chambers. In the present instance I retain the general plan of construction, but improve upon the mode of making the groups of spheres and the manner of arranging them, so as to form a section or slab of a steam-generator.

In figs. 1, 2, and 3, A and A' represent two spheres, united by a neck, B, and this group is united above and below to other spheres by bolts designated by dotted lines a a.

It has been found that the groups are more apt to break at the necks than elsewhere; hence I introduce a strengthening-web, b, extending across the inside of the neck, as indicated in the drawing, this web being readily formed in the mold, so as to be cast with and form a part of the cast-iron group.

It is this strengthening-web which constitutes the first part of my invention.

Heretofore it has been my practice in arranging the cast-iron spheres and groups of spheres, and securing them together by bolts so as to make a slab or section for a steam-generator, to make the joints between the groups rigid and unyielding, in consequence of which leakage sometimes occurred at the joints, owing to the unequal expansion and contraction of the slabs.

In order to remedy this, I, in my patent of August 4, 1868, introduced what I termed compensating units among the rigidly-joined spheres which composed the slab; that is, units connected to the others with ball-and-socket joints, so that the slab might possess the property of yielding to unequal expansion and contraction wherever these compensating units occurred in the slab.

In the present instance, however, all the joints are made of the ball-and-socket character, and the spheres are so arranged in forming the slab or section that the latter is capable of yielding at every point where a joint occurs.

It will be seen on reference to fig. 1, that where the tubular projection of the sphere A meets that of the sphere B, the joint is of the ball-and-socket character, the dotted line x representing the spherical continuation of the joint; hence one sphere can move freely to the limited extent permitted by the tie-bolt, independently of the other, without impairing the tightness of the joint. It should be understood, however, that in carrying out my invention, the double spheres should be connected together, as shown in fig. 4; that is, one tubular projection, t, of one double sphere, P, should be jointed to one double sphere, M, and the other tubular projection, t', of the said double sphere P, should be jointed to another double sphere P, disconnected from the double sphere M, and this should be continued throughout the series.

This arrangement, however, involves the occasional introduction of single spheres at the ends of the slabs, as for instance the single sphere N, which is connected to one leg of the double sphere M.

If, however, several slabs or sections have to be united, one or more of what appear to be single spheres in fig. 4 may be actually double spheres, providing one of the spheres forms a part of one slab and the other sphere part of an adjoining slab, as shown in the sectional plan view, fig. 5, where portions of two slabs are connected together transversely by the double sphere P.

Claims.

1. A strengthening-web, b, arranged in the neck between two spheres, substantially as set forth.
2. A slab or section composed of spheres, arranged and jointed as herein set forth.

In testimony whereof I have signed my name to this specification in the presence of two subscribing witnesses.

JOSEPH HARRISON, JR.
